(57) **CLAIM**

The ornamental design for an electronic atomizing device, as shown and described.

DESCRIPTION

FIG. 1 is a perspective view of an electronic atomizing device showing our design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines consisting of evenly spaced dash lines in the drawings depict portions of the electronic atomizing device that form no part of the claimed design.
